HOISTING AND PULLING IMPLEMENT

Leo Haubert, Tulsa, Okla.

Application December 3, 1945, Serial No. 632,462

6 Claims. (Cl. 254—75)

1

This invention relates to hoisting and pulling implements wherein lever-operated devices are provided with an automatic release control whereby the operator may advance a take-up chain step by step, or withdraw the pulling implement along the chain step by step, without contacting any portion of the device except the operating lever.

One of the important objects of the present invention is the provision in a pulling implement of chain hooks of unequal length arranged to contact laterally extending cross-pins on the take-up chain, such hooks being pivoted upon an operating lever in positions preventing crossing of the chain hooks during operation.

Another object of the invention is the provision of a detachable frame readily positioned upon the pulling implement whenever it is desired to use the pulling implement against an object, as for example, in a load-binder. The detachable frame also serves as a chain guide whenever applied.

A further object of the invention is the arrangement in a pulling implement of chain hooks of unequal length cooperating with a special take-up chain so that the chain may be advanced or retracted a half-link on each stroke of the operating lever, and whereby the longer hook always operates on the taut end of the take-up chain and the shorter hook always engages the slack end thereof.

Other objects and advantages will be apparent from the following description wherein reference is made to the accompanying drawings illustrating a preferred embodiment of my invention, and wherein

Fig. 1 is a side elevation of my improved hoisting and pulling implement;

Fig. 2 is a plan view thereof, with parts shown in section along line 2—2 of Fig. 1;

Fig. 3 is a fragmentary side elevation showing positions assumed while the longer hook is being advanced;

Fig. 4 is a view similar to Fig. 3 showing positions assumed when the shorter hook is being advanced;

Fig. 5 is a fragmentary side elevation showing positions assumed by the handle and associated parts preparatory to retraction of the shorter hook;

Fig. 6 is a view similar to Fig. 5 showing positions assumed during the retraction of the shorter hook;

Fig. 7 is a fragmentary side elevation showing positions assumed by the handle and associated

2

parts preparatory to retraction of the longer hook;

Fig. 8 is a view similar to Fig. 7 showing positions assumed during the retraction of the longer hook;

Fig. 9 is a view similar to Fig. 7 showing the completion of the retractive movement of the longer hook;

Fig. 10 is a detail vertical section taken substantially along the line 10—10 of Fig. 11;

Fig. 11 is a vertical cross-section taken substantially on the line 11—11 of Fig. 10;

Fig. 12 is a side elevation of my improved hoisting and pulling implement equipped with a detachable frame for special uses;

Fig. 13 is a detail vertical cross-section taken substantially on the line 13—13 of Fig. 12; and

Fig. 14 is a detail vertical section taken substantially on the line 14—14 of Fig. 13.

Referring now to the drawings, reference numeral 10 designates the operating lever of my improved hoisting or pulling implement. Lever 10 is forked at its lower extremity and pivoted on trunnions 11 in the forward ends of clevis 12, which carries at its rear portion a swivel 13 and hook 14 for engagement with a suitable anchorage whenever it is desired to use the pulling implement. As shown in Fig. 2, the trunnions 11 extend on opposite sides of clevis 12 for a distance suitable to permit their mounting in detachable frame 15 whenever desired (note Fig. 12). The detachable frame 15 is intended for use only when my improved implement is utilized for binding a load or other operations where the pulling is exerted against some object, and is unnecessary when the pulling implement is utilized for guywire tightening, et cetera.

Upper chain hook 16 and lower chain hook 17 are pivotally mounted in the fork of lever 10 at equal distances above and below trunnions 11. These chain hooks are of unequal length and extend forwardly. They are formed at their free ends with laterally spaced hook portions 16^a and 17^a respectively, for engagement with the laterally extending cross-pins 18 of the take-up chain 19. These hook portions 16^a and 17^a are substantially identical in shape, but face each other. Each is formed with a sloping end portion 16^b or 17^b forwardly of the recess 16^c or 17^c in which the cross-pins of the take-up chain are adapted to seat. The sloping end portion 16^b or 17^b engages and rides upon the cross-pin 18 next forwardly of its then position when the chain is advanced, being held in engagement

therewith by the springs 20 and 21 (Fig. 12). When the hook portions are advanced sufficiently by the throw of lever 10, such cross-pins 18 enter hook recesses 16^a or 17^a because of the pressure of the same operating springs 20 and 21. Between the hook portions 16^a and 17^a at the sides the chain hooks 16 and 17 are grooved to form upper and lower guides for the chain 19, a central rib on each hook being arranged to provide strength with light weight. Operating spring 20 engages the upper (shorter) chain hook 16 to press it into engagement with the chain at all times, and a similar operating spring 21 engages the lower (longer) chain hook 17 to press it into engagement with chain 19. As best shown in Figs. 10 and 12, each operating spring 20 and 21 is centrally looped about the pivot of its respective hook, with one end extending into engagement with a pin mounted on the hook at a substantial distance from its pivot. The opposite ends of the operating springs are formed into eyes for the reception of a cross-link 22 connecting the springs for mutual interaction in exerting uniform pressure on the hooks, both springs 20 and 21 cooperating with each other in flexibly maintaining pressure upon both hooks at all times.

The take-up chain 19 is preferably permanently associated with the pulling implement, and carries a hook 23 or similar work-engaging means at its forward extremity and a ring 24 at its rear extremity to prevent accidental disengagement of the take-up chain from the pulling implement. This ring 24 also affords a good hand-hold to enable the operator to take up any loose slack before he starts the lever take-up operations. The chain 19 herein is shown as comprising alternate pairs of flat links 19^a and 19^b respectively, the inner flat links 19^a being in lateral contact with each other and spacing outer links 19^b from each other, as best shown in Fig. 2. Cross-pins 18 extend through and on each side of four laterally aligned link portions and forms the pivots on which the chain links swing. This arrangement permits spacing of cross-pins 18 at convenient short intervals to enable advancing or retracting the take-up chain 19 through short distances at each stroke without bringing the chain hooks into engagement with other portions of the links than the cross-pins 18. It will be obvious that this arrangement permits advance and retraction through step-by-step movements of one-half link at each stroke and that the distance between cross-pins may be varied at will.

As best shown in Fig. 2, the ring 24 on the rear end of take-up chain 19 is left open a distance greater than the thickness of one of the flat links 19^a but less than that of two of such flat links. To engage ring 24 upon the take-up chain one flat link 19^a is inserted into the open portion of the ring, the ring passed through the opening in such link, and then the second flat link 19^a swung into position in the open portion of the ring and the ring partially rotated. Obviously, the ring can be readily removed whenever desired, but will not become accidentally disengaged during take-up operations. This improved ring feature provides means for quickly assembling my pulling implement on the job and for easy removal of chain 19 from the pulling implement for transporting or replacement.

An automatic release arm 25 is pivotally mounted on lower chain hook 17 by a pin 26, and is normally pressed forwardly under tension by a coil spring 27, here shown as centrally looped

around pin 26 with one end pressing against the bottom of chain hook 17 and its other end passing through a slot in cross-pin 26. The head of cross-pin 26 is drilled for a cotter key 28 which engages at its loop end a tension pin 25^a mounted on the automatic release arm 25 at a suitable distance from the cross-pin 26, substantially as shown. Projecting from the side of upper chain hook 16 are a pair of release pins 29, 30 spaced for suitable engagement with portions of the release arm 25. As shown in Figs. 3-9, the upper release pin 29 and lower release pin 30 respectively, engage with offset and slotted portions of release arm 25, the tension spring 27 maintaining the release arm constantly in contact with one or the other of the release pins. The release mechanism is controlled through operating lever 10 and will function at the will of the operator without requiring any resetting or manual adjustment.

To advance the take-up chain 19, as when it is desired to tighten a guywire or operate a hoist, the operating lever 10 is swung rearwardly until lower chain hook 17 hooks over the cross-pin of chain 19 next forward, excess slack having previously been taken up by manually pulling on the chain through the ring 24. Operating lever 10 is then swung forward until upper chain hook 16 hooks over the cross-pin 18 next forward of the cross-pin with which it had been engaged. This operation may be continued as long as desired, the lower hook and then the shorter upper hook advancing one cross-pin at a time in a series of step-by-step advances, and without the hooks crossing each other at any time. It will be noted that the lower hook 17 always operates upon the taut forward portion of the take-up chain while the shorter upper hook 16 always operates upon the slack rear portion of the take-up chain. Moreover, one or both of the chain hooks 16 or 17 are always in engagement with the take-up chain 19, so that it is impossible for the take-up chain to become accidentally disengaged. When operating lever 10 is stationary in either of its forward or backward positions, both chain hooks 16 and 17 are engaged with cross-pins in the take-up chain.

To release the take-up chain whenever desired, the operating lever 10 is swung forward and backward the same as when the chain is taken up except that the operating lever is swung a little further in both directions. To release the upper chain hook 16, the operating lever 10 is pushed forward until the automatic release arm 25 engages the upper release pin 29, substantially as shown in Fig. 5. Operating lever 10 is then swung rearwardly and upper chain hook 16 is held out of engagement from and passes over one cross-pin in the take-up chain. As the operating lever continues to swing rearwardly, the lower release pin 30 comes into contact with the release arm 25 (note Fig. 6) and disengages it from the upper release pin 29, whereupon the upper chain hook 16 is released and again pressed down by spring 20 into engagement with the chain, hooking over the second cross-pin in the take-up chain from that it had just engaged. When the operating lever 10 is in its rearmost position, the automatic release arm 25 engages the lower release pin 30, substantially as shown in Fig. 7, and when the operating lever is swung forwardly the lower chain hook 17 is held out of engagement from and passes over one cross-pin in chain 19. As lever 10 continues to swing forwardly, the upper release pin 29 comes into con-

tact with the release arm 25 (note Fig. 8) and disengages it from the lower release pin 30, whereupon the lower chain hook 17 is released and pressed by spring 21 into engagement with the chain 19, hooking over the second cross-pin from that which it had just engaged. Both chain hooks 16 and 17 are then again engaged with take-up chain 19 and ready either to further release the take-up chain or again advance it, at the will of the operator.

To maintain the upper hook 16 out of engagement with the take-up chain 19 when the take-up chain is being released, I preferably provide a guide spring 31 between upper hook and chain. As best shown in Fig. 10, this guide spring is anchored on the pivot pin of the upper hook 16, extends forwardly therefrom into engagement with the take-up chain and has its forward extremity curved around the central rib section of the upper chain hook 16. This guide spring is particularly useful when the pulling implement is used in a vertical or inverted position.

To make the automatic release arm 25 fool-proof whenever desired, I provide a resilient disengagement holder 32. As best shown in Figs. 3-9, the disengagement holder is pivoted on the automatic release arm 25 and formed with a lower portion adapted to snap into one of two spaced recesses 33 and 33^a in the release arm. The upper portion of the disengagement holder 32 is formed as a loop which is located behind the slotted upper portion of the automatic release arm 25 as long as the lower portion of the disengagement holder 32 is kept in the forward recess 33. When the lower portion of the disengagement holder is swung rearwardly into the rear recess 33^a, the looped upper portion of the disengagement holder is moved into position forwardly of and closing the slotted upper portion of release arm 25 and so preventing the release arm from effectively engaging either the upper or lower release pins 29 or 30. This disengagement holder is a safety feature and need only be used while it is desired to prevent the take-up chain 19 from being released.

The detachable frame 15 may be added to the pulling implement whenever it is desired to use such implement against an object, as in binding a load. The detachable frame is formed with brackets 15^a adjacent its rear extremity having U-shaped openings arranged to serve as bearings for trunnions 11 of the operating lever 10. Caps 15^b held in place by removable cotter keys close the upper portions of the trunnion bearing openings. Adjacent its forward extremity the frame 15 is formed with a chain guide bracket 15^c of greater length than the distance between adjacent cross pins 18 and open at its top to permit the insertion of the take-up chain without removing the take-up chain 19 from the pulling implement. To thread the take-up chain 19 through the guide bracket 15^c, the take-up chain 19 must be slack so that one link of the chain can be held in a vertical position (note Fig. 14), whereupon one cross-pin of the chain can be moved from front to rear through the bracket 15^c, the then vertical link passing between the sides of the guide bracket, after which the vertical link is permitted to fall into alignment with the remainder of the take-up chain. To disengage the take-up chain it is merely necessary to reverse such movement, swinging one link with its cross-pin into vertical position above the guide bracket 15^c, and then moving such

raised cross-pin forwardly to release the chain from the guide bracket.

To thread the take-up chain 19 into the pulling implement between upper and lower hooks 16 and 17, it is only necessary to hold the hooks apart. This is accomplished by manually separating the hooks 16 and 17 until the top offset portion on the release arm 25 engages under the lower release pin 30. When in this position the release arm 25 will not become disengaged from release pin 30 until such release arm is manually swung rearwardly. While the chain hooks 16 and 17 are held in this open position, the take-up chain 19 is easily passed therebetween and pulled out any desired distance within the limits of its length. It will be noted that the central portions of the hooks are shaped to guide the chain. Accordingly, when the take-up chain is threaded into position and the automatic release arm 25 is again swung out of engagement with the lower release pin 30, the chain is snugly positioned and the pulling implement is ready for immediate use.

From the foregoing description it will be seen that my improved hoisting and pulling implement is made of very few, relatively inexpensive and rugged parts. It is sufficiently powerful to do the work of many heavy, cumbersome and expensive machines while its compactness and light-weight adapt it to ready transportation and a wide variety of uses.

Obviously the present invention is not restricted to the particular embodiments herein shown and described. It is not indispensable that all the features of the invention be used conjointly, since they may be employed advantageously in various combinations and sub-combinations. Various changes and modifications may be made in the details of construction and design without departing from the spirit and scope of the invention as defined in the following claims.

I claim:

1. A pulling and hoisting implement, comprising a forked lever, a fulcrum device therefor, a take-up chain having laterally extending cross-pins, upper and lower operating hooks pivoted on opposite sides of the lever fulcrum, springs pressing said hooks toward the chain, and release means pivotally mounted upon one of said hooks and actuated upon excess movement of the lever in either direction to hold either hook out of engagement with one cross-pin only as the lever is rocked.

2. A pulling and hoisting implement, comprising a forked lever, a fulcrum device therefor, a take-up chain having laterally extending cross-pins, upper and lower operating hooks pivoted on opposite sides of the lever fulcrum, springs pressing said hooks toward the chain, and release means including a release arm pivotally mounted on one hook, a pair of spaced pins carried by the other hook in position to be contacted by said release arm, and a spring pressing said release arm into engagement with one or the other of said pins.

3. A pulling and hoisting implement as recited in claim 2 provided with disengagement-preventing means comprising a member pivoted on said release arm and swingable to a position engaging said pins in advance of said release arm.

4. A pulling and hoisting implement, comprising a forked lever, a fulcrum device therefor, a take-up chain, operating hooks pivoted on opposite sides of the lever fulcrum, resilient means pressing said hooks toward the chain for engage-

ment with a portion of a link thereof, and release means pivotally mounted upon one of said hooks and actuated upon excess movement of the lever in either direction to hold either hook out of engagement with one link only as the lever is rocked.

5. A pulling and hoisting implement, comprising a forked lever, a fulcrum device therefor, a take-up chain, operating hooks pivoted on opposite sides of the lever fulcrum, means yieldingly pressing said hooks toward the chain, and release means including a release arm pivotally mounted on one hook, a pair of spaced pins carried by the other hook in position to be contacted by said release arm, and means yieldingly pressing said release arm into engagement with one or the other of said pins.

6. A pulling and hoisting implement, comprising a forked lever, a fulcrum device therefor, a take-up chain, operating hooks pivoted on opposite sides of the lever fulcrum, means yieldingly pressing said hooks toward the chain, release means including a release arm pivotally mounted on one hook, a pair of spaced pins car-

ried by the other hook in position to be contacted by said release arm, means yieldingly pressing said release arm into engagement with one or the other of said pins, and disengagement preventing means comprising a member pivoted on said release arm and swingable to a position engaging said pins in advance of said release arm.
